SHOE SEWING MACHINE

Alfred R. Morrill, deceased, late of Woodstock, Vt.,
by Ruth W. Morrill, administratrix, Woodstock,
Vt., assignor to United Shoe Machinery Corpora-
tion, Flemington, N. J., a corporation of New
Jersey

Application May 29, 1948, Serial No. 30,109

6 Claims. (Cl. 112—59)

1

The present invention relates to improvements in shoe sewing machines, and more particularly to an improved thread tension control mechanism which is particularly adapted for use in shoe sewing machines for releasing and holding the thread tension in the released condition for the sewing of a plurality of stitches upon the starting of the machine.

The invention is shown in a preferred form as embodied in an automatic shoe sewing machine of the general type illustrated in the patent to Morrill No. 2,359,662, having a chainstitch sewing mechanism adapted for sewing a chainstitch seam in which the chain is laid on the outer or welt side of the seam, and an automatic shoe support including a jack and supporting and actuating mechanism for positioning a jacked shoe with relation to the sewing mechanism and for transferring the operation about the sole margin of the shoe. In the illustrated machine, provision is made for the automatic severing and clamping of the thread and for the release of the thread tension when the machine is stopped, and for re-establishing the thread tension in active operation only after the first stitch of the new seam has been sewn when the machine is again started. Reference may be had also to the disclosure of Morrill Patent No. 2,359,663, in which provision is made for re-establishing the thread tension in active operation only after a plurality of initial stitches of the new seam have been sewn when the machine is started.

The thread tensioning device of the illustrated construction is of the general type which comprises a tension wheel about which the thread passes, a tension control element in the form of a friction brake lever movable between tension engaging and tension release positions, and spring means tending to bias the tension control element to its tension engaging position.

It is the object of the present invention to provide a novel and improved mechanism to release and to hold the thread tensioning device in released position during the sewing of at least the first two stitches of a new seam, and thereafter to re-establish the tensioning device in operation.

In accordance with the invention, a novel construction and arrangement of the mechanism for releasing and for re-establishing the thread tension is provided, which consists of two independently operated latching devices which operate consecutively to hold the tension control element of the tensioning device in its inoperative position during the sewing of the first two stitches of a seam, one of said latching devices being arranged to be automatically released by the oscillatory

2

movement of the bell-crank clutch shifting lever during the formation of the first stitch of the new seam, and the other of said latching devices being arranged to be automatically released by the oscillatory downward movement of the take-up lever upon completion of the second stitch to permit the engagement of the thread tension.

With the above noted and other objects in view as may hereinafter appear, the several features of the invention consist also in the devices, combinations and arrangement of parts hereinafter described and claimed, which together with the advantages to be obtained thereby will be readily understood by one skilled in the art from the following description taken in connection with the accompanying drawings, in which Fig. 1 is a view in left side elevation of an automatic inseam shoe sewing machine, illustrating particularly the sewing head and portions of the motor drive with the parts in stop position, only so much of the machine being shown as is believed necessary to illustrate the connection of the present invention therewith; Fig. 2 is a plan view of substantially the parts shown in Fig. 1, but with portions broken away and sectioned to illustrate particularly the construction and operation of the sewing cam stop motion mechanism; and Figs. 3, 4 and 5 are somewhat fragmentary views of the thread tension release mechanism illustrating successive positions of these parts taken during the sewing of the first two stitches of the seam; Fig. 3 illustrating a position in which the machine stop arm has moved out of its slot and the thread tension brake lever is supported by the release latch controlled by the oscillatory movement of the bell-crank clutch shifting lever; Fig. 4 illustrating a later position of the parts in which the first-mentioned latch has moved to release position so that the thread tension brake lever is supported by the release latch operated by the take-up lever; and Fig. 5 illustrating the final operating position of the parts in which the thread tension brake lever is fully released and has moved against the cooperating disk to reestablish the thread tension in operation.

The machine disclosed in the drawings is an automatic machine for sewing the welt and upper to the insole of a welt shoe, which is similar to the machine illustrated in the patent to Morrill No. 2,359,662 above referred to, and comprises generally a sewing head having a curved hook needle arranged to enter the work from the welt side, and associated thread handling and work guiding devices for sewing the insole of a welted shoe, a shoe supporting jack and pattern control mechanism for imparting turning, tip-

ping and feeding movements to the jack and shoe supported thereon to transfer the point of operation about the margin of the shoe sole, and driving and stopping mechanism arranged to operate automatically at the completion of a sewing operation to release and to move the jacked shoe away from the sewing mechanism, and to return the several operating mechanisms of the machine to a convenient starting position. Only so much of the machine has been illustrated and will be hereinafter described, as is believed necessary to illustrate the connection of the present invention thereto.

In the drawings, the sewing head 22 of the machine is illustrated in Fig. 1 together with a portion of the motor housing 24 mounted thereon, and a small portion of the column 26 on which the sewing head is carried. The drive for the machine is taken from a motor 52 in the housing 24 directly downwardly to the sewing head 22 to the stop motion of the machine and to the sewing cam shaft 54, and thence downwardly to the pattern mechanism of the machine (not here shown). As generally indicated in the drawings (Figs. 1 and 2), the armature shaft 56 of the motor is connected through reduction gears 58, 60 to drive a vertically arranged driving shaft 62 which is in turn connected by means of gears 64, 66 to drive an externally coned clutch member 68 forming the driving element of the main driving clutch. The clutch member 68 is supported against movement axially and is sleeved to a vertically arranged main drive shaft 70 to turn loosely thereon. These parts are driven continuously. The cooperating driven element of the main driving and stopping clutch comprises an internally coned clutch member 72 keyed to turn with and to slide on the drive shaft 70. A compression spring (not shown) coiled about the drive shaft 70 tends normally to hold the driven clutch member 72 in a raised disengaged position with relation to the driving clutch member 68. The driven member 72 of the main starting and stopping clutch is arranged through its splined connection with the vertical drive shaft 70 to drive the pattern mechanism of the machine including the pattern cam shaft. The driven clutch member is also connected to drive the sewing cam shaft 54 through the meshing engagement of a spiral gear 74 formed on the outer periphery of the driven clutch member 72 with a spiral gear 76 secured to the sewing cam shaft 54. Disengagement of the main driving clutch will operate to disconnect the drive to each of the sewing head and the pattern mechanism of the machine.

In stopping the machine, the sewing cam shaft is first brought to a gradual stop, and is then driven to a predetermined position in a reverse direction by means of slow speed reverse driving connections and a friction clutch mechanism on the sewing cam shaft. The sewing cam shaft stopping and reversing clutch mechanism is arranged to be thrown into operation as the main clutch 72 is disengaged in stopping the machine. As shown in Figs. 1 and 2, the reverse driving connections comprise a forwardly extending reverse drive shaft 78 which is continuously driven from the gear 64 through the engagement therewith of a worm gear 80 on the shaft 78. An extension 79 coupled to the forward end of the reverse drive shaft 78, carries a worm 82 which meshes with a worm gear 84 loosely sleeved on the sewing cam shaft 54. The gear 84 has formed integrally therewith, an internal cone-shaped internal clutching surface 86, and forms the driving

element of the sewing cam shaft reverse and stopping clutch. The cooperating driven member of this clutch consists of a clutch element 88 which is provided with a cooperating external coned clutch surface, and is keyed to turn with and to slide axially on the sewing cam shaft 54. A compression spring 90 coiled about the sewing cam shaft 54 and arranged to bear at one end against the sleeve hub of the driven clutch member 88 and at its other end against a disk 92 secured to the cam shaft tends normally to maintain the clutch in open position. The sewing cam shaft reversing and stopping clutch is actuated by means of a bell-crank clutch shifting lever 94 which carries on one arm thereof a roller 96 engaging in a cam track 98 in the sleeve hub of the shiftable clutch member 88. During normal operation in which the clutch is disengaged, the bell-crank clutch shifting lever 94 has an idling motion determined by the contours of the cam track 98. At the same time that the main clutch 72 is disengaged in stopping the machine, a vertically arranged lock bolt 100 carried in the rearwardly extending end of a lock bolt carrier or slide 102 is permitted to engage within a socket formed in the free end of the bell-crank 94. The slide 102 is supported in a casing 104, and is acted upon by a compression spring 106 coiled about a reduced portion of the slide which tends to maintain the same in a fully extended rearward position. During this operation of stopping and reversing the sewing cam shaft, the bell-crank clutch shifting lever 94 and slide 102 will be moved forwardly against the pressure of the spring 106, and then rearwardly to the final stop position of the machine illustrated in Fig. 1.

In order to stop the sewing cam shaft 54 in its predetermined stop position, a stop arm 108 is provided which is loosely supported at its upper end on a transversely extending pivot shaft 110 located substantially above the sewing cam shaft, and at its lower end is provided with a roller 112 for engagement with a cam disk 114 on the sewing cam shaft 54. During the normal rotational movement of the sewing cam shaft in a counter-clockwise direction as viewed from the left side of the machine, the roller 112 is held out of engagement with the cam disk 114. However, during the reverse movement of the sewing cam shaft in stopping the machine, the roller 112 is arranged to engage with and ride inwardly in a stop cam groove 116, so that as the roller 112 reaches the bottom of the groove 116, the cam shaft is brought to a positive stop.

The operation of the main starting and stopping clutch 72 of the machine and of the lock bolt 100 in starting and stopping the machine, is controlled from a vertically arranged starting treadle rod 118 through connections which include a rock shaft 120 extending transversely of the machine. The rock shaft 120 is provided at one end with a forked lever arm 122 which straddles the treadle rod 118 and engages beneath a compression spring 124 coiled about the treadle rod. At its upper end the rock shaft 120 is seated against a collar 126 fixed to the treadle rod. A forked clutch control lever 128 secured to the rock shaft 120 is rendered operative by the downward movement of the treadle rod to move the main clutch member 72 downwardly into engaging position. For controlling the operation of the lock bolt 100, there is also secured to the rock shaft 120, a downwardly and rearwardly extending lever arm 130 which carries a roller 132

adapted for engagement against a cam surface formed on a lever arm 134 secured to a rock shaft 136 parallel to and beneath the rock shaft 120. A lever arm 138 on the rock shaft 136 is connected by a link 140 with the lower end of the lock bolt 100. A compression spring 142 coiled about a reduced portion of the lock bolt and seated at its lower end in the slide 102 acts to force the lock bolt 100 yielding upward. A tension spring 144 connected between the lever arm 130 and a point on the machine frame tends to rock the shaft 136 in a direction to permit the disengagement of the main clutch and the movement of the lock bolt upwardly into engagement with the socket in the clutch shift lever 94.

Downward movement of the treadle rod 118 in starting the machine, will act as above noted, to engage the main clutch 72 and at the same time to effect a withdrawal and disengagement of the lock bolt 100 from the clutch shift lever 94, thus permitting the sewing cam shaft reverse stop motion clutch member 88 to be moved under the pressure of its spring to an inoperative running position.

The sewing mechanism of the machine, as indicated generally in Fig. 1, consists of a chain-stitch sewing mechanism adapted for sewing the upper and welt to the insole of a welt shoe, the parts including a curved hook needle 150, a looper 152, a thread finger 154, a take-up lever 156, a welt guide 158, and a channel guide 160. In the illustrated construction, the thread finger 154 takes the form of an arcuate member slidably supported within a casing 162 and arranged upon stopping the machine, to be moved rearwardly an abnormal amount to cause the thread to be firmly gripped by a normally inoperative cooperating anvil member. The gripped thread is severed from the work by means of a thread severing knife 164. For a full description of this mechanism which forms specifically no part of the present invention, reference may be had to the patent to Morrill No. 2,359,662, dated October 3, 1944, illustrating a similar construction and arrangement of the sewing instrumentalities.

The take-up lever 156 of the machine, as best shown in Fig. 1, is supported to turn on a pivot 168 and is given a continuous oscillatory movement by means of a cam on the cam shaft 54. The take-up lever is arranged to act against a thread tension provided by a tension wheel 170 (see Figs. 1 and 2) to draw in the previous stitch, and thereafter to draw off additional thread from the supply to the tension wheel. Tension is supplied by means of a brake lever 172 and brake shoe 174 which engages with a friction drum secured to turn with the tension wheel 170 under variable pressure determined by a tension spring 176 connected between the brake lever 172 and take-up lever 156. The brake lever 172 is rigidly secured on the pivot shaft 110 to turn as a unit therewith. As shown in Fig. 1, the thread drawn from the supply passes around the tension wheel 170, and thence around an idler pulley 178, around a take-up pulley 180 on the take-up lever 156, around an idler 182, and thence to the looper 152.

In accordance with the invention, mechanisms are provided which operate in a novel and improved manner to control the position of the thread tensioning assembly including the brake shoe 174, brake lever 172 and rock shaft 110 to cause the thread tension to be released when the machine is stopped, and thereafter to be re-established when the machine is again started only after the first two stitches have been formed.

Mechanism provided for controlling the position of the thread tensioning assembly includes a downwardly extending arm 184 which is secured to the rock shaft 110 and which is actuated by the operation of the lock bolt mechanism in stopping the machine to disengage the thread tension. The arm 184 at its lower end is arranged to be engaged by an abutment 186 on the lock bolt carrier 102 during the initial forward movement of the lock bolt carrier, so that the rock shaft 110 and brake lever 172 are rocked in a counterclockwise direction as viewed in Fig. 1, to disengage the friction brake shoe 174. The thread tension brake assembly including the brake lever 172, shoe 174 and rock shaft 110 are thereafter held positively in the fully disengaged position of Fig. 1, when the machine is stopped by the operation of the stop arm 108 previously described, which is loosely supported on the rock shaft 110. The reverse movement of the cam shaft 54 during the operation of the machine stop motion causes the stop lever 108 to ride into its slot 116 so that it is rocked in a counterclockwise direction, thus causing the abutment adjacent the base or pivotal support of the lever to engage and to move a stop pin 190 formed on a yoke-like extension 194 rigidly connected with the brake lever 172 and rock shaft 110. The brake lever 172 and shoe 174 are forced in a counterclockwise direction to the final stop position shown in Fig. 1. It will be evident from a consideration of Figs. 1 and 2, that the yoke-like extension 194 is formed integrally with the brake lever 172, and passes around the tension wheel 170 to provide a rigid support for the pin 190 at the opposite side of the tension wheel from the brake lever 172.

When the machine is started, the forward rotation of the cam shaft 54 in a counterclockwise direction as shown, for example, in Fig. 3, causes the roller 112 to ride out of its slot 116 to release the pin 190 and brake lever 172 supported thereby. The brake lever 172 and thread tension brake shoe 174 are, however, held in a retracted inoperative position during the formation of the first two stitches by means of the stop arm 108 and two separate release latch mechanisms which are successively released to permit the re-establishing of the thread tension. One of the release latches referred to, is operative when and after the stop arm 108 has moved out of its slot in starting the machine to continue to support the brake lever 172 and supporting rock shaft 110 in inoperative position while the first stitch of the new seam is formed and is drawn in. The other of the release latches referred to, is operative at the time the first latch is released, to continue the support of the brake lever 172 and rock shaft 110 in an inoperative position until finally released after a second stitch of the new seam has been drawn in.

The first of the release latch mechanisms referred to, consists of a release latch 200 supported intermediate its length on a stationary pivot pin 202, and at its forward end provided with a notched surface adapted for engagement with an abutment 204 on the downwardly extending arm 184. A compression spring 206 seated at one end in a recess in the lock bolt carrier casing 104, and at its other end bearing against the under side of the release latch 200, tends to rock the latch in a counterclockwise direction to the latching position, shown in Fig. 3. At its rear end the release latch 200 carries a roller 208 adapted for engagement with a cam

surface 210 formed in the upper side of the bell-crank lever 94. It will be noted that when the release latch 200 is rocked clockwise to inoperative position as shown in Figs. 4 and 5, by movement of the roller 208 onto the high portion of its cam 210, the forward end of the latch is engaged against a downwardly and forwardly inclined surface 212 formed on the downwardly extending arm 184.

Referring specifically to Figs. 1, 2 and 3, it will be seen that as the cam shaft starts its rotary movement in a counterclockwise direction upon starting the machine, and as the stop arm 108 rides out of its slot to release the thread tension brake lever 172, the bell-crank lever 94 is rocked in a counterclockwise direction from the position of Fig. 2, so that the cam surface 210 is moved forwardly to the right, the roller 208 of release latch 200 rides onto the low portion of its cam 210, and the release latch 200 is thus brought into the operative latching position to support the parts of the tension brake mechanism in the inoperative position shown in Fig. 3. At a substantially later point in the sewing cycle, the oscillatory bell-crank 94 is again rocked in a clockwise direction, causing the roller 208 to ride onto the high portion of the cam surface 210, and thus to release the latch 200 as shown in Fig. 4. As previously noted, the forward end of the latch is thus brought into engagement with the inclined cam surface 212 of the downwardly extending arm 184, so that the latch is held in its inoperative position against the pressure of its spring 206.

After the release latch 200 has been moved to its released position during the formation of the first stitch of the new seam as shown in Fig. 4, the thread tension brake lever 172 and brake shoe 174 continue to be held in a retracted inoperative position through the operation of a second release latch mechanism which is subsequently tripped by the thread take-up lever 156 during its downward or return movement after the second stitch has been drawn in. The later operated release latch mechanism referred to, consists of a depending latch 216 supported on a pivot pin 218 and provided at its lower end with a hook 220 which is adapted to engage beneath the tip of a forwardly extending arm 222 formed integrally with the tension release brake lever 172. A torsion spring 224 coiled about the pivot pin 218 acts to urge the latch 216 in a clockwise direction against the member 222. A horizontally disposed release latch trip member 226 is pivotally supported from the latch 216, and is provided at its forward end with a downwardly extending hook 228 which is arranged for engagement in a notch 230 formed in the hub of the thread take-up lever 156. A set screw 232 adjustably mounted in the trip member 226 is arranged for engagement with a cammed surface 234 on the hub of the take-up lever 156, and acts during the downward movement of take-up lever 156 to effect the disengagement of the latch hook 228 from the notch 230 when the take-up lever 156 has moved downwardly a sufficient distance to cause the notch 230 and hook 228 engaged thereby to move the latch 216 to its released position. A stop screw 236 carried on a stationary lug 238 is adapted for a rearward position of the latch 216 to engage with the tail of the trip member 226, so that for a final running position of the parts shown in Fig. 5, the trip member 226 will be held in the raised inoperative position.

The operation of the later operated latch

mechanism to permit the re-establishing of the thread tension after the second stitch of the new seam has been pulled in, is briefly as follows: The movement of the first-mentioned latch mechanism including latch lever 200 to its released position as shown in Fig. 4, permits the parts of the thread tension assembly including rock shaft 110, brake lever 172 and the forward extension 222 thereof to be rocked in a clockwise direction so

that the extension 222 is brought into engagement with the hook 220 of the latch 216, this being substantially the position shown in Fig. 4. During the subsequent operation of the machine, the take-up lever 156 moves in a counterclockwise direction to draw in and tighten the second stitch of the new seam and to draw off additional thread from the supply. Thereafter, as the take-up lever 156 starts its downward movement, the hook 228 of trip member 226 now engaged in the notch 230 in the hub of the take-up lever 156 as shown in Fig. 4, is drawn forwardly so that the latch 216 and hook 220 are withdrawn from their position of supporting engagement with the extension 222, and will permit the parts of the thread tensioning assembly including the brake lever 172 and brake shoe 174 to be moved under the influence of tensioning spring 176 to the fully operative tensioning position of Fig. 5. As the take-up lever 156 now continues its movement toward the limiting down position, the stop screw 232 on the trip member 226 contacting with cam surface 234 moves the hook 228 of the trip member out of engagement with the notch 230, so that the latch 216 is permitted to swing rearwardly in a clockwise direction into engagement with the cammed upper edge of the extension 222. At the same time the tail of the trip member 226 will have engaged the stop screw 236, causing this element to be rocked to an inoperative position out of engagement with the hub portion of take-up lever 156 again as shown in Fig. 5. It will be noted that the continued rocking movement of the thread tensioning assembly including rock shaft 110 and the depending arm 184 in a clockwise direction, will cause the forward end of the latch 200 engaging the cammed surface 212 to be further rocked in a clockwise direction against the pressure of its spring 206, so that roller 208 is moved wholly out of engagement with the co-operating cam surface 210 of the oscillating bell-crank 94.

It will be understood that the invention is not limited to the specific embodiment shown, and that various deviations may be made therefrom without departing from the spirit and scope of the appended claims.

What is claimed is:

1. In an inseam shoe sewing machine operable in accordance with a recurring stitch forming cycle, the combination of a sewing mechanism including a sewing cam shaft, a curved hook needle, a needle threading device, a thread tensioning device including a tension control element movable between tension establishing and tension release positions, and means biasing said element toward tension establishing position, and a driving and stopping mechanism for the sewing cam shaft, means operative in stopping the machine to support said element in tension release position, and means operative in starting the machine to re-establish the thread tension comprising a pair of latches successively operable to support said tension control element in stepped inoperative positions, and latch release devices acting in different timed relation to the cyclical

operation of the sewing mechanism for moving said latches successively to latch release position, whereby said first latch is released to cause the tension control element to be supported by the second latch during a first stitch forming cycle, and the second latch to be released to re-establish the thread tension during a second stitch forming cycle.

2. In an inseam shoe sewing machine, the combination of a sewing mechanism operable in accordance with a recurring stitch forming cycle including a hook needle, a needle threading device, a thread take-up lever, a sewing machine stop mechanism including a normally oscillatory actuating member, a thread tensioning device including a tension control element movable between tension engaging and tension release positions, and means biasing said element toward tension engaging position, a thread tension control device including means operative in stopping the machine to move said element to tension release position, and means operative in starting the machine to re-establish the thread tension comprising a pair of latches successively operable to support said element in stepped inoperative positions, a connection actuated by said oscillatory actuating member during a first stitch forming cycle to move one of said latches to latch release position, and a connection controlled by said thread take-up lever to release the second latch and thereby to permit movement of the tension control element to tension engaging position during a second stitch forming cycle of the machine.

3. In a shoe sewing machine operable in accordance with a recurring stitch forming cycle, the combination of a hook needle, a needle threading device, a thread take-up lever, a thread tensioning device including a tension control element movable between tension engaging and tension release positions, and means biasing said element toward tension engaging position, and a sewing machine stop mechanism including a normally oscillatory actuating member, and a thread tension control device including means operative when the machine is stopped to move said control element to inoperative position and to permit the tension on the thread to be re-established when the machine is started only after a plurality of stitches of the new seam have been formed, comprising a latch mechanism first operative when the machine is started to support the control element in inoperative position, and arranged to be released by movement of said oscillatory member in the first stitch forming cycle, and a second latch mechanism operative thereafter to support the control element in an inoperative position and arranged to be released by the movement of the take-up lever in the second stitch forming cycle.

4. In a shoe sewing machine having a hook needle, a needle threading device, a thread take-up, a thread tensioning device including a tension control element movable between tension engaging and tension release positions and means for biasing said element toward tension engaging position, a sewing machine reverse stop mechanism including a stop arm arranged to be rocked between a running and a stop position, and a normally oscillatory stop mechanism actuating member, the combination of a thread tension control device which comprises a connection actuated by said stop arm to move the tension control element to inoperative position when the machine is stopped, a latch mechanism first operative upon

return of the stop arm to running position when the machine is started to latch the thread tension control element in inoperative position during formation of the first stitch, and thereafter to be tripped into latch release position, and a second latch mechanism arranged to support the thread tension control element in inoperative position when the first latch mechanism is released and to be tripped into latch release position after a second stitch is pulled in and thereby to permit the return of the control element to tension engaging position.

5. In a shoe sewing machine having cyclically operable sewing mechanism including a hook needle, a needle threading device, a thread take-up, a thread tensioning device including a tensioning brake lever, and means for biasing said brake lever to tension the thread, and a sewing machine reverse stop mechanism including a stop arm arranged to be rocked between a running and a stop position, a thread tension control device which comprises a connection rendered operative by movement of the stop arm to stop position to support the brake lever in inoperative position, and a first and a second latch mechanism operable independently of one another for supporting the brake lever in inoperative position, and latch release devices acting in different timed relation to the cyclical operation of the sewing mechanism for moving each of said latch mechanisms successively to latch release position, whereby said first latch mechanism is operative to support the brake lever in inoperative position and is thereafter released upon completion of the first stitch of a new seam, and said second latch mechanism is operative to support the brake lever when the first latch mechanism is released and is thereafter released to release the brake lever and re-establish the thread tension upon completion of a second stitch.

6. In a shoe sewing machine having a hook needle, a needle threading device, a thread take-up, a thread tensioning device including a tensioning brake lever and means for biasing said brake lever to tension the thread, and a sewing machine reverse stop mechanism including a stop arm arranged to be rocked between a running and a stop position, and a normally oscillatory stop mechanism actuating member, the combination of a thread tension control device which comprises a connection operative upon movement of the stop arm to stop position to support the brake lever in inoperative position, a pair of latches independently operable for supporting the brake lever in inoperative position during the sewing of initial stitches of a new seam, a latch release device acting in timed relation to the cyclical operation of the sewing mechanism for rendering one of said latches inoperative upon completion of a first stitch, and means for holding said latch in said released position, a second latch release element operative cyclically with the machine timed to move said second latch to its latch position prior to the release of the first-mentioned latch, and thereafter to move said second latch from its latch position to permit the engagement of the brake lever in the second stitch forming cycle, and means active when the brake lever is engaged to render said second latch release element inoperative.

RUTH W. MORRILL,
Administratrix of the Estate of Alfred R. Morrill,
Deceased.
